UNITED STATES PATENT OFFICE.

LELAND L. FOSS, OF VIDALIA, GEORGIA.

COTTON-GIN.

1,207,288.

Specification of Letters Patent.

Patented Dec. 5, 1916.

Application filed May 22, 1916. Serial No. 99,176.

To all whom it may concern:

Be it known that I, LELAND L. Foss, a citizen of the United States, resident of Vidalia, in the county of Toombs and State 5 of Georgia, have made a certain new and useful Invention in Cotton-Gins; and I declare the following to be a full, clear, and exact description of the same, such as will enable others skilled in the art to which it 10 appertains to make and use the invention, reference being had to the accompanying drawings, and to letters or figures of reference marked thereon, which form a part of this specification.

15 Figure 1 is an end view of the invention. Fig. 2 is a central vertical section of the same. Fig. 3 is a detail perspective view of a hacker frame and connections. Fig. 4 is a similar view showing a modified crank leg. 20 Fig. 5 is a side view of a cotton gin showing further modifications of the crank leg. Fig. 6 is a detail perspective view of the stay bar.

The invention has relation to cotton gins 25 of the double roller type, designed for operation upon long fiber or sea island cotton, having for its object to provide an improved construction of the hacker frames and of the crank legs of the operating mechanism for 30 said frames.

Other objects and advantages will herein-after appear.

The invention consists in the novel construction and combinations of parts, as hereinafter set forth.

In the accompanying drawings, illustrating the invention, the numeral 2 designates the main frame of the machine, having end uprights 3; 4 designates the ginning rollers, 40 one at each side of the machine; 5 the breasts, located respectively above the rollers and carrying the ginning blades 6, coöperating with the rollers and with the hacker blades hereinafter referred to; 7 the shed boards, inclined respectively toward the rollers, to feed the cotton thereto; 8 the seed griddles projecting toward the rollers, and 10 the hacker blades forming the side bars of vibratory hacker frames 12, and 13 are 45 the reciprocatory feeders, mounted and sliding upon the griddles toward and away from the rollers.

The power or crank shaft is shown at 14, an endless belt 15 engaging pulley 14' upon 50 said shaft and passing upwardly and obliquely around the inner side of the driv-

ing pulley 16 for one ginning roller, thence engaging pulley 17, movable to adjust the tension of the belt as hereinafter described, the belt passing next downwardly and engaging the driving pulley 16' for the other ginning roller, and thence to the pulley 14'. A driving belt 19 for the feeder shaft engages a pulley 20 upon the shaft of one of the ginning rollers, passing thence to a 65 pulley 21 upon the feeder shaft, a device 22 for adjusting the tension being provided for this belt.

The breasts pass at their ends through perforations or slots of the end frames, and 70 have outer downturned lugs 23, said breasts being suspended from vertical bolts 24, axially adjustable to vertically adjust the breasts, within horizontal slots or flanges 25 of the end uprights, nuts 26 upon said 75 bolts providing for this adjustment. The breasts are also horizontally adjustable through adjustment of upper and lower horizontal bolts 27, 27', said bolts at their ends pivotally engaging the stems of upper and 80 lower bolts 28, 28, carried by the breasts, the lower bolts 27 at their outer ends engaging vertical slots 28' of flanges 30 of the end uprights, and the upper bolts 27' being connected respectively by turnbuckles 29', the 85 adjustment of said upper and lower horizontal bolts being effected by means of the nuts 29 thereon and of the turnbuckles 29', said nuts bearing against said flanges. Upon 90 suitable differential adjustment of the horizontal bolts, together with adjustment of the vertical bolts 24, the breasts may be obliquely 95 adjusted to one side or the other, in an arcuate path, to give an oblique or leaning adjustment to the ginning blades with respect to the rollers, the blades moving from their tangential lines of contact with said rollers as centers. Upon suitable adjustment of the horizontal and vertical bolts the breasts 100 may be adjusted toward or away from each other, or they may be adjusted vertically.

Coiled springs 40 surround the bolts 24, said springs bearing at their upper ends against the flanges 25, and at their lower ends bearing against the breasts, through the medium of nuts 41 and washers 41' upon the nuts, whereby the breasts may move upwardly in a yieldable manner against the tension of the springs, in case of strain upon the ginning blades brought about usually by 105 wads of lint, in the upward movement of the hacker blades. The tension of the 110

springs is varied by adjustment of the nuts 41. In this way, the tension of the springs of each breast may be adjusted independently and made greater or less for one breast than for the other, as is required in some cases.

Each hacker frame 12, including the central shaft 12', the oppositely extending arms 12² and the hacker blades 10 at the outer ends of said arms, is preferably made in one integral casting, and each V-form frame 30, depending from the hacker frame and connected to the crank of the power shaft by crank leg 38, is also made in one integral part or casting, including a lower rod or shaft 30' and upwardly extending diverging branches 30², joined to said shaft at their lower ends, and at their upper ends each provided with a laterally extended rest 31 for the hacker blade and with an upwardly extending, perforated, flattened portion or lug 31', engaged by a securing screw 32 to connect the same with the hacker blade.

In Fig. 4 of the drawings a modification of the V-form frame is shown, having four upwardly extending branches 30 instead of two as in the first form of said frame, and in Fig. 5 a further modification is shown wherein two of these diverging branches are located in a vertical plane and the other two located in an inclined plane, this form of the device being suitable for use at the ends of the machine to avoid, in certain cases, necessity for intermediate supports for the crank shaft.

By making the hacker frame, including the shaft, the oppositely extending arms and the blades, in one integral part, and the V-form frame 30 in another single integral part, many extra parts shown in my Patent No. 730,449, dated June 9, 1903, are dispensed with, and the construction and the connections much simplified, rendering the device more easily assembled and lessening the parts liable to work loose.

The crank shaft is supported in bearings of the end frames, and in order to provide intermediate supports for this shaft I prefer to provide a longitudinal stay bar 39, secured at its end to the end frames and of ridged angle form, the ridge presenting upwardly, and carrying the intermediate jour-

nal boxes 41, said stay bar being slotted at 42 for passage of the cranks and the ends 55 of the crank legs in their rotation.

The pulley 17 is mounted at one end of a lever 43, said lever being fulcrumed at 44 in a support 45 upon the main frame of the machine, and having a slot 46 engaged by a bolt 47 upon the handle end of the lever. To adjust the tension of the belt 15, the nut 48 upon said bolt is loosened, the lever moved to the necessary extent, the bolt working in the slot, and the nut being tightened 65 to secure the adjustment.

I claim:

1. In a cotton gin, the combination with ginning rollers, breasts carrying ginning blades and a hacker frame having blades 70 coöperating with the ginning blades, of means for operating said hacker frame comprising a cranked power shaft, a V-form frame having a lower transverse rod and upwardly extending diverging branches integral with said rod, said branches having each at its upper end an integral perforated lug, and a securing bolt engaging said perforation and securing said lug to the hacker blade, and a crank leg connecting said transverse rod with the crank of the power shaft. 75

2. In a cotton gin, end frames having vertical and horizontal flanges, a ginning roller, a breast provided with overlying end extensions and vertical bolt extensions 85 engaging the slots of said horizontal flanges, a ginning blade carried by each breast and adapted to contact tangentially with said roller, upper and lower oppositely extending horizontal bolts having at their adjacent 90 ends pivotal engagement with said end extensions, the lower of said bolts having at their outer ends engagement with the slots of said vertical flanges and nuts bearing against said flanges, turnbuckles connecting 95 the approximated ends of said upper bolts, and coiled springs surrounding said vertical bolts and bearing at their upper ends against said horizontal flanges and at their lower ends against said breast. 100

In testimony whereof I affix my signature, in presence of two witnesses.

LELAND L. FOSS.
